Design No. 526

Joseph Pratts Design for an Open Top Place Franklin Stove.

Drawn and Engraved by B. Morris, Bratt & Co.

Dated October 16, 1802

Fig. 1.

Fig. 2.

Fig. 3.

Joseph Pratt of Boston Mass
Assignor to
Bowers, Pratt & Co. of Boston aforesaid
Letter Patent No 526 Dated Nov 16th 1852.

The schedule referred to in these Letters Patent and making part of the same

To all Persons to whom these Presents shall come,

Be it known that I Joseph Pratt of Boston in the County of Suffolk, and State of Massachusetts have invented or produced a new and useful ornamental design for an open Fireplace Franklin Stove and I do hereby declare that the same is fully represented in the accompanying drawings of which Figure 1 is a top view of the stove. Figure 2 a front elevation of it. Figure 3 an inner side view of one of the jambs. Figure 4 a horizontal section of the side jamb and the pilaster against which it abuts, said section being taken on line from A to B of Figure 3. Figure 5 is a vertical central and transverse section of the same.

In the said drawings C denotes the hearth or hearth plate of the stove whose outer boundary in front of the face plate and around the bases of the pilasters is composed of fillets and mouldings as seen in the drawings, the first or lower moulding being an ovolo. This is surmounted by a fillet and a cavetto. Next above the cavetto is a ledge on or above which rises a fillet above which is an ovolo, another fillet, and an ogee which latter rises in alto relief above the main or plane upper surface of the hearth.

On the hearth the front plate of the stove rests, this plate being composed of two panelled pilasters D D surmounted by an arched and panelled frieze E E. The ornaments in the panels of the frieze are a rosette in the centre, and scrolls of leaf work flanking it on both sides. A chain work ~~has~~ relief is extended on the front of the arch.

The top plate of the stove is shown at F. The projection of it over the front plate, and sides plates constitutes a moulded cornice the character of whose mouldings is seen in the drawings. This top plate is surmounted by a flat elliptic dome or rising which is intended for the reception of a water vase or any other ornamental article. The character of the mouldings bordering the rising is shown in the drawings.

The back plate is seen at H. It is panneled and in the panel is an ornament in bas relief like that seen in panel of the jamb plate represented in Figure 3. Over the back plate is a panneled inclined plate I which connects with two jamb plates K K.

The grate is seen at T, its front upright part being composed of Gothic fence work as seen in Figure 2.

Having thus described the parts of the said fire place and represented the ornamental design of the whole I would remark that I claim as new and of my production the said ornamental design substantially as exhibited in the drawings and above explained.

In testimony whereof I have hereto set my signature this tenth day of September A. D. 1852
